COMBINED MEMORANDUM PAD AND NOTE HOLDER

William B. MacKrell, Minneapolis, Minn., assignor to Standard Packaging Corporation, New York, N.Y., a corporation of Virginia

Filed Sept. 15, 1960, Ser. No. 62,158

Term of patent 7 years

(Cl. D74—1)

FIG. 1

FIG. 5

FIG. 1 is a perspective view of a combined memorandum pad and note holder showing my new design;

FIG. 2 is a top plan view thereof as it appears with the indicator moved to a different position;

FIG. 3 is a side elevational view;

FIG. 4 is a front elevational view; and

FIG. 5 is a rear elevational view thereof.

The dotted line showing of the note paper is for illustrative purposes only.

I claim:

The ornamental design for a combined memorandum pad and note holder, as shown and described.
